RETRACTING TYPE THEATER CHAIR

Joseph G. Prosser and Thomas W. Prosser, Pasadena, Calif., assignors to American Seating Company, Grand Rapids, Mich., a corporation of New Jersey

Application June 26, 1946, Serial No. 679,362

6 Claims. (Cl. 155—116)

1

The present invention relates to chairs and more particularly to chairs of the retracting type for use in theaters, auditoriums and the like. This application is a continuation-in-part of our pending application Serial No. 679,354, filed June 26, 1946.

The primary objects of the invention are to provide an improved chair of the retracting type wherein the occupant may move the seat rearwardly in order to permit others to pass in front of him without his having to rise from the seat; to provide such a chair having a link mechanism for mounting the chair back and seat, which mechanism insures easy and comfortable forward and rearward movements and which is concealed below the level of the chair seat; to provide such a chair which when retracted occupies a minimum of space in the rear of the chair; to provide such a chair having improved means for mounting on spaced chair-supporting standards; and in general to provide such a retracting chair which is efficient in operation, reasonably economical in manufacture and attractive in appearance.

Illustrative embodiments of the invention are shown in the accompanying drawings, wherein:

Figure 1 is a perspective view of a retracting chair showing the chair seat and back in their normal, forward positions for occupancy;

Figure 2 is a perspective view similar to Figure 1 showing the chair seat and back in their retracted positions;

Figure 3 is a fragmentary front elevational view of the lefthand side of the chair;

Figure 4 is an inside elevational view of the mounting and operating mechanism at the left hand side of the chair, certain parts being shown in vertical section taken on line 4—4 of Figure 3, and the movable chair parts being shown in their forward positions;

Figure 5 is an inside elevational view similar to Figure 4 and showing the movable chair parts in their rearward positions.

Referring now in detail to these drawings and referring first to Figures 1 through 5 in particular, the retracting chair there shown is mounted on a frame comprising spaced, upright, chair-supporting standards 1 having inwardly projecting lugs 2 thereon provided with vertical stud-receiving slots 3, mounting members 4 having outwardly turned flanges 5 with depending threaded studs 6 adapted to fit into the slots 3, nuts 7 threaded on the lower ends of the studs 6, and a transverse bar 8 secured as by welding to the opposite mounting members. The frame

2

thus formed is of sturdy and rigid construction. If desired, members 9 of rubber, cork or other resilient material may be interposed between the flanges 5 of the mounting members and the lugs 2 on the standards for absorbing any vibration of the chair during its retracting and returning movements.

The mounting and operating mechanisms on opposite sides of the chair being of like construction, only one side is shown in Figures 3-5 and hereinafter described. A pair of side plate supporting links comprises a front supporting link 10 and a rear supporting link 11 which have their lower ends pivotally connected to the mounting member 4. A side plate 12 of generally triangular shape is pivotally connected at its lower forward corner to the upper end of the front supporting link 10, and is pivotally connected in its rearward portion to the rear supporting link 11 slightly below the upper end of said link 11. The side plate 12 is thus mounted for forward-rearward movement with the supporting links, and for simultaneous turning or rocking movement.

A seat carrier 13 has its rearward portion pivotally connected to the lower rear corner of the side plate 12. The forward portion of the seat carrier 13 is supported by means of a curved seat supporting link 14 having its lower end pivotally connected to a lug 15 on the seat carrier 13, and having its upper rearward end pivotally connected to the upper end of the rear supporting link 11 by means of a pin 16 which as shown passes through an arcuate slot 17 in the side plate 12 and which is freely movable in said slot.

A chair back 18 is mounted on inwardly turned flanges 19 of the side plates 12 on opposite sides of the chair, as by means of screws 20. The chair seat 21 is shown rigidly secured to the seat carriers 13 on opposite sides of the chair as by means of bolts or rivets 22, but the seat may if desired be mounted on said seat carriers turnably about a horizontal axis.

It will be seen that when the chair is retracted, the seat moves rearwardly in a substantially straight path, while the back moves rearwardly and also assumes a near-vertical position thus to minimize the space required for retraction in the rear of the chair. Rearward movement of the chair is stopped by contact of the rear supporting links 11 with rubber stops or bumpers 23 on the mounting members 4, while forward movement of the chair is stopped by the contact of said links 11 with similar stops or bumpers 24 on the mounting members 4.

An equalizing strut 25 is here shown secured

as by welding to the rear supporting links 11 on opposite sides of the chair so that these links are rigidly secured in assembly and move in unison, thus adding to the stability of the structure.

It will thus be seen that a retracting chair has been provided having a novel combination of supporting links for the chair back and seat, in which the mounting and operating mechanism is located out of sight below the seat level, and which mechanism is arranged for easy and comfortable forward-rearward movements of the chair. While but several specific embodiments of the chair have been herein shown and described, it will be understood that numerous details of the construction shown may be altered or omitted without departing from the spirit of the invention as the same is defined by the following claims, wherein the word "frame" is to be construed broadly enough to include either a unitary assembly or a pair of spaced chair standards whose only rigid connection is the floor upon which such pair of standards is installed.

We claim:

1. In a chair, a frame, front and rear supporting links having their lower ends pivotally connected to the frame, a chair back connected to the upper ends of said supporting links and movable forwardly and rearwardly therewith, a chair seat having its rearward portion connected to the chair back, a seat supporting link connected to the forward portion of the seat and to a rear supporting link for supporting the forward portion of the seat, and stop means for limiting the forward and rearward movements of the supporting links.

2. In a chair, a frame, front and rear supporting links having their lower ends pivotally connected to the frame, side plates mounted on the upper ends of the supporting links for forward and rearward movements with said links, a chair back mounted on the side plates, a chair seat pivotally connected at its rear to the chair back, a seat supporting link connected to the forward portion of the seat and to a rear supporting link for supporting the forward portion of the seat, and stop means for limiting the forward and rearward movements of the side plates.

3. In a chair, a frame, front and rear supporting links having their lower ends pivotally connected to the frame thus forming pairs of links on opposite sides of the chair, side plates having pivotal connections with the upper ends of the links in said pairs respectively, a chair back mounted on the side plates, a chair seat pivotally connected at its rear to the chair back, a seat-supporting link connected to the forward portion of the seat and with a rear supporting link for supporting the forward portion of the seat, and stop means for limiting the forward and rearward movements of the side plates.

4. In a chair, a frame, front and rear supporting links having their lower ends pivotally connected to the frame thus forming pairs of links on opposite sides of the chair, side plates having pivotal connections with the upper ends of the forward links in said pairs respectively and pivotal connections with the corresponding rearward links below the upper ends thereof, a chair back mounted on the side plates, a chair seat pivotally connected at its rear to the side plates, seat-supporting links connected to the forward portion of the seat and to the upper ends of the rear supporting links for supporting the forward portion of the seat, and stop means for limiting the forward and rearward movements of the side plates.

5. In a chair, spaced upright chair-supporting standards, mounting members attached to the standards, front and rear supporting links having their lower ends pivotally connected to the mounting members, a chair back connected to the upper ends of said supporting links and movable forwardly and rearwardly therewith, a chair seat having its rearward portion connected to the chair back, a seat supporting link connected to the forward portion of the seat and to a rear supporting link for supporting the forward portion of the seat, and stop means for limiting the forward and rearward movements of the supporting links.

6. In a chair, spaced upright chair supporting standards, mounting members attached to the standards, front and rear supporting links having their lower ends pivotally connected to the mounting members thus forming pairs of links on opposite sides of the chair, side plates having pivotal connections with the upper ends of the forward links in said pairs respectively and pivotal connections with the corresponding rearward links below the upper ends thereof, a chair back mounted on the side plates, a chair seat pivotally connected at its rear to the side plates, seat supporting links connected to the forward portion of the seat and to the upper ends of the rear supporting links for supporting the forward portion of the seat, and stop means for limiting the forward and rearward movements of the side plates.

7. In a chair, spaced upright chair supporting standards, mounting members attached to the standards, front and rear supporting links having their lower ends pivotally connected to the mounting members, a chair back connected to the upper ends of said supporting links and movable forwardly and rearwardly therewith, a chair seat having its rearward portion connected to the chair back, a seat supporting link connected to the forward portion of the seat and to a rear supporting link for supporting the forward portion of the seat, and stop means for limiting the forward and rearward movements of the side plates.
